Inventor:

United States Patent Office.

WILLIAM S. COLBURN, OF LOAMI, ILLINOIS.

Letters Patent No. 65,727, dated June 11, 1867.

IMPROVEMENT IN CANT-HOOKS.

The Schedule referred to in these Letters Patent and making part of the same.

TO ALL WHOM IT MAY CONCERN:

Be it known that I, WILLIAM S. COLBURN, of Loami, in the county of Sangamon, and State of Illinois, have invented a new and improved Cant-Hook; and I do hereby declare that the following is a full, clear, and exact description thereof, which will enable others skilled in the art to make and use the same, reference being had to the accompanying drawings, forming part of this specification, in which—

Figure 1 is a side view of my improved cant-hook.

Figure 2 is a detail sectional view of a portion of the same taken through the line x x , fig. 3.

Figure 3 is a front view of the lower portion of the same.

Similar letters of reference indicate like parts.

My invention has for its object to furnish an improved cant-hook which may be quickly and conveniently adjusted to the different-sized logs to be handled, and it consists in the combination of the notched hook, bolt, slide, and plate with each other, as hereinafter more fully described.

A is the wooden bar to which the hook is attached, which is made in the usual form, and the lower part of which is slotted for the reception of the hook. The hook B passes through the slot in the bar A, and through a slot in the plate E, and has its forward edge notched, as shown in figs. 1 and 2. The plate E is securely attached to the bar, and has three staples or slotted flanges attached to or formed upon it. D is a forked slide, the stem of which passes through and works in a hole in the flange or staple e' . Through the forward end of the branched arms of the slide D passes the bolt C, which fits into the notches of the hook B, as shown in fig. 2. The ends of the bolt C pass through the slots of the flanges or staples e^2 e^3 , and are kept from working out of place by a head formed upon one end and a nut placed upon the other. The slide D is held back, holding the bolt securely against the notched edge of the hook, by the coiled spring d' coiled around the stem of the said slide, the rear end of which rests against a pin passing through the said stem, and its other end rests against the rear side of the staple or flange e' .

The principal use of the flanges or staples e^2 and e^3 is to prevent the slide D from being forced out from the bar A and bent or broken, should the instrument by accident fall hook downwards.

I claim as new, and desire to secure by Letters Patent—

The cant-hook, consisting of the forked slide D, bolt C, hook B, and lever A, constructed and operating in the manner herein described.

The above specification of my invention signed by me this 20th day of August, 1866.

WILLIAM S. COLBURN.
